UNITED STATES PATENT OFFICE.

HENRY C. EGERTON, OF PASSAIC, NEW JERSEY; MAY L. EGERTON EXECUTRIX OF SAID
HENRY C. EGERTON, DECEASED.

TELEPHONE RECEIVER.

Application filed April 5, 1922. Serial No. 549,800.

This invention relates to telephone receivers, but it is well understood by those skilled in the art that a telephone receiver may also be used as a transmitter and the 5 invention may therefore be said to relate to both telephone receivers and transmitters although it is contemplated that it will be found of more useful application in connection with the receivers.

10 This invention further has reference to that class of telephone receivers wherein the magnetic flux in the permanent magnets is not affected by changes in the telephonic currents but in which soft iron pole pieces are employed and the changes in magnetism in the operation of the instrument consists simply in shifting the magnetism from one portion of the soft iron pole pieces to other portions, the flux through the permanent magnets being substantially unchanged.

15 The main object of the present invention is to simplify and render more efficient instruments of the character described.

20 As ancillary to the foregoing object, it is an object of the invention to provide an improved armature construction and mounting.

25 It is a further object of the invention to provide improved coil securing means, and it is a further object of the invention to provide an improved magnetic structure.

30 Other and ancillary objects of the invention will appear hereinafter.

35 In the accompanying drawings which illustrate the invention:—

Fig. 1 is a side elevation of an instrument embodying the invention;

40 Fig. 2 is a vertical central section of the instrument of Fig. 1, on an enlarged scale and with the horn partially broken away;

Fig. 3 is a section on the line 3—3 of Fig. 2;

45 Fig. 4 is a section on the line 4—4 of Fig. 2;

Fig. 5 is a diagrammatic view showing the relative connections and arrangements of the electric coils; and

50 Fig. 6 is a diagrammatic view showing a modified arrangement of the windings.

Referring to the drawings, the apparatus comprises a casing of cast brass having a body 1 from which extend the supporting legs 2 spaced 120° from each other and a 55 cover 3 having a central opening surrounded

by the threaded boss 4 to which the horn 5 is secured. Clamped between the cover 3 and the flat brass ring 6 is a diaphragm 7 which may be of mica. Secured against the ring 6 is a permanent magnet 8 of the horse shoe type. Secured in magnetic relation to the poles of this magnet are two flat soft iron pole pieces 9 and 10, the pole piece 9 being clamped directly against the magnet while the other is spaced therefrom by 60 sheet iron shims 11. The ring 6, permanent magnet, shims and pole pieces are secured to the cover by screws 12. The ends of the pole pieces overlap as shown and the overlapping ends are bifurcated to form respectively the legs 13, 14, 15 and 16 on which are respectively mounted the coils 17, 18, 19 and 20.

These coils are connected in series as shown in the diagram of Fig. 5 and are so wound and relatively connected that the coils on the two legs of a pole piece have opposite magneto-motive forces so that upon the passage of current the magnetism of one of the legs is weakened and the other 75 strengthened. The two pole pieces and their coils are so constructed and connected that the leg of one pole piece which has its magnetism strengthened on passage of current through the coils is opposite the leg 80 of the other pole piece which has its magnetism weakened. For instance in the structure shown, upon passage of current through the coils the magnetism of the legs 13 and 16 will be weakened, while the magnetism 85 of the legs 15 and 14 will be strengthened. 90

The terminals of the loop in which the coils are connected are connected to the binding posts 21 and 22 mounted in but insulated from the casing, the wires of the 95 telephone circuit being connected with the binding posts upon the exterior of the casing.

It will be seen that the pole pieces overlap each other and their bifurcated ends or legs are adapted to come against the coils on the opposing pole pieces respectively so as to hold these coils upon the legs. This forms a secure and simplified manner of securing the coils.

Between the bifurcated ends of the pole pieces is mounted an iron armature 23 which is supported by a flat spring 25 of non-magnetic material such as phosphor bronze, secured at one end to the lug 24 110

- fastened to the pole piece 9, and at the other end secured by soldering, brazing or in other suitable ways to the armature 23 at a point substantially midway of its ends.
- 5 To one end of this armature is secured by soldering, brazing or in other suitable ways, a bronze wire or operating rod 26, the other end of this rod being secured to a diaphragm 7.
- 10 It will be observed that the only points of engagement of the armature with other objects are where it engages the spring 25 and the diaphragm operating rod 26. This leaves the system of diaphragm and connected armature extremely free in its movement and sensitive to variations in the telephonic current. By suitable adjustment the spring may be torsionally stressed so as to place the connected armature and diaphragm in a desired state of tension, and the flat spring 25 provides a torsional spring serving to properly position the armature and provide the necessary spring opposition to the movement of the armature under 25 changes in the magnetic action caused by changes in the telephonic currents. The spring 25 thus combines in one element, whereby simplification is realized, and by a single point of engagement with the armature whereby sensitiveness of the instrument is increased, both the pivotal support of the armature and the spring positioning means therefor. The spring serves to maintain the armature so that it does not touch the pole 30 pieces and is adapted to do this independently of any supporting effect of the diaphragm so that the terminal on the diaphragm may be made any that is desired without considering the supporting of the armature, and 35 the movable element consisting of the spring, armature and diaphragm should be of such mass and qualities as to provide the proper natural frequency for the instrument.
- 40 It will be noted that the spring upon which the armature is mounted may be referred to as of the cantilever type, that is, having support at one side of the load only, the other end being free.
- 45 It will be seen that the instrument is most simple in construction and that the receiving mechanism is mounted upon the cover so that it can be readily removed for inspection or repair. It will also be seen that 50 the shims 11 serve to space one of the pole pieces from the magnet in an adjustable manner whereby the spacing between the pole pieces can be suitably adjusted.
- 55 From the foregoing it will appear that 60 when the telephonic current in the coils varies, the armature will be given a rotative movement about its point of support, the direction in which the armature turns depending upon whether the current through 65 the coils is increasing or decreasing and that

any movement from the normal is opposed by the action of the spring. The armature, and through it the diaphragm, will therefore oscillate in response to variation of current in the coils.

70 Instead of winding the pole pieces as in the device of Figs. 1 to 5, the armature may be wound and the pole pieces, unwound. The instrument may be otherwise in all particulars the same as that of Figs. 1 to 5, the modification being shown in Fig. 6 wherein the bifurcated legs 13', 14', 15' and 16' are unwound while the armature 23', is provided with a winding 27 wound continuously in the same direction and producing one 75 magnetic pole at one end of the armature and a magnetic pole of opposite polarity at the other end of the armature. One end of the armature will therefore be drawn in one direction and the other end of the armature in the other direction whereby a rotative movement of the armature about its point of support is produced, this movement being resisted by the supporting spring. The armature will therefore vibrate in response 80 to variations of current in the winding and, if the current reverses the armature will turn from one side of its normal position to the other.

85 While the invention has been illustrated in what are considered its best applications it may have other embodiments without departing from its spirit and is not therefore limited to the structures shown in the drawings.

90 What I claim is:—

95 1. A telephone instrument comprising in combination a permanent magnet of the horseshoe type, bifurcated pole pieces of magnetic material secured in magnetic relation to the poles of said magnet respectively and located upon one and the same side of the major plane of said magnet, an armature rotatively mounted between said pole pieces and coils mounted on the legs of said pole pieces respectively and wound and connected to produce rotative movement of said armature on change of current through said coils and a diaphragm connected with said armature.

combination a permanent magnet of the horse shoe type, bifurcated pole pieces of magnetic material secured in magnetic relation to the poles of said magnet respectively and located upon one and the same side of

5 the major plane of said magnet, an armature rotatively mounted between said pole pieces and coils mounted on the legs of said pole pieces respectively and wound and connected to produce rotative movement of said armature on change of current through said coils and a diaphragm connected with said armature, said pole pieces being spaced at different distances from said magnet

10 15. 4. A telephone instrument comprising in combination a permanent magnet of the horse shoe type, bifurcated pole pieces of magnetic material secured in magnetic relation to the poles of said magnet respectively, an armature rotatively mounted between said pole pieces and coils mounted on the legs of said pole pieces respectively and wound and connected to produce rotative movement of said armature on change of current through said coils and a diaphragm connected with said armature, and means for adjustably spacing said pole pieces in relation to said magnet.

20 25. 5. A telephone receiver comprising in combination a magnet, an armature adapted to be acted upon by said magnet, coils adapted to affect the movement of said armature, a single spring upon which said armature is mounted and which provides a pivotal mounting therefor, and a diaphragm connected with said armature.

30 35. 6. A telephone receiver comprising in combination a magnet, an armature adapted to be acted upon by said magnet, coils adapted to affect the movement of said armature, a single torsional spring adjacent the free end of which said armature is mounted and which provides a pivotal mounting therefor, and a diaphragm connected with said armature.

40 45. 7. In a telephone instrument the combination with a permanent magnet of the horse shoe type, of flat, soft iron, bifurcated pole pieces, one of said pole pieces being directly secured to said magnet and means spacing the other pole piece at a distance from said magnet, a flat spring secured to one of said pole pieces, an armature secured to the end of said spring, a diaphragm, and means for connecting one end of said armature with said diaphragm, and coils mounted respectively upon the legs of said pole pieces, said coils being wound and connected to produce rotative movement of said armature upon change of current through said coils.

50 55. 8. A telephone instrument comprising in combination a magnet, pole pieces for said magnet and coils on said pole pieces, said pole pieces respectively being adapted to

abut against the coils of their opposing pole pieces to prevent the coils from sliding off their respective pole pieces, an armature between said pole pieces and a diaphragm connected with said armature.

50 55. 9. A telephone instrument comprising in combination a magnet, pole pieces for said magnet, said pole pieces overlapping each other and coils on said pole pieces, said pole pieces respectively being adapted to abut against the coils of their opposing pole pieces to prevent the coils from sliding off their respective pole pieces, an armature between said pole pieces and a diaphragm connected with said armature.

60 65. 10. A telephone instrument comprising in combination a casing comprising a body portion and a cover, a diaphragm, a permanent magnet and flat, bifurcated pole pieces of soft iron secured in magnetic relation to said magnet and upon one and the same side of the major plane thereof, said pole pieces being spaced at different distances from said magnet, coils upon said pole pieces, a torsional spring secured to one of said pole pieces, an armature between said pole pieces and mounted upon said spring and means connecting said armature with said diaphragm, said magnet, pole pieces, coils, spring, armature and diaphragm being mounted upon said cover.

70 75. 11. A telephone receiver comprising, a flat horseshoe permanent magnet, substantially flat pole pieces associated with each end of said magnet, a substantially flat armature held in operative relation to said pole pieces by an elastic means, a diaphragm connected to said armature, means for holding said parts in operative relation and means for changing the distribution of magnetic flux through said armature and pole pieces.

80 85. 12. In a telephone receiver a substantially flat horseshoe permanent magnet, a substantially flat faced bifurcated pole piece mounted on each end of said magnet, a substantially flat armature, a single torsional spring adjacent the free end of which said armature is mounted and a diaphragm connected to one end of said armature.

90 95. 13. In a telephone receiver a substantially flat horseshoe permanent magnet, a substantially flat faced bifurcated pole piece mounted on each end of said magnet, a substantially flat armature held in operative relation between said pole pieces by a single, cantilever type, torsional spring which is supported on one of said pole pieces and which has its major plane substantially at right angles to the plane of the pole pieces and a diaphragm connected to one end of said armature.

100 105. 14. In a telephone receiver a substantially flat horseshoe permanent magnet, flat pole pieces associated with each end of said magnet, said pole pieces each being mounted on

the same side of said magnet, a flat armature in operative relation to and mounted between the ends of said pole pieces, the major planes of all of said members being parallel,
5 said armature being maintained in operative relation to said pole pieces by a single torsional spring whose major plane is at right

angles to the plane of said pole pieces, said spring being supported by one of said pole pieces.

In testimony whereof I have signed this specification this first day of April, 1922.

HENRY C. EGERTON.
